UNITED STATES PATENT OFFICE.

GEORGE W. PITTMAN, OF BUSHWICK, NEW YORK.

IMPROVEMENT IN MACHINERY FOR TWISTING FIBROUS SUBSTANCES.

Specification forming part of Letters Patent No. **22,745**, dated January 25, 1859.

To all whom it may concern:

Be it known that I, GEORGE W. PITTMAN, of Bushwick, in the county of Kings and State of New York, have invented a new and useful Improvement in Machinery for Spinning and Twisting Fibrous Substances; and I do hereby declare that the following is a full, clear, and exact description of the same, reference being had to the accompanying drawings, forming part of this specification, in which—

Figure 1 is a longitudinal central section of a machine illustrating my invention. Fig. 2 is a plan of the same.

Similar letters of reference indicate corresponding parts in the two figures.

This invention consists in a certain mode of applying a flier or its equivalent, in combination with other mechanism herein described, whereby it is made to spin a sliver or roving, and by the same operation to twist the yarn thus produced along with one or more yarns or threads which have been previously spun, and by that means a saving of half the mechanism commonly employed and half the time commonly occupied in the spinning operation for the manufacture of twist may be effected.

The invention is applicable either in the production of strands for rope, or for cotton, woolen, or silk twist for all purposes.

To enable others skilled in the art to make and use my invention, I will proceed to describe its construction and operation.

A is a suitable framing containing the bearings for the flier B and other mechanism employed. The flier B has an opening c through the center of each of its heads a a', and it contains a bobbin C, which is fitted to turn on a central spindle b, attached to one or both the heads a a' in such a manner as not to interfere with the central openings c c'. The said bobbin C carries yarn d d, which has been spun by the usual or any convenient means previously to its being introduced to this machine. Near one end of the flier there is arranged a pair of rollers D D', which are arranged in bearings on the frame A, and between which the sliver or roving e e, which is to be first spun and then twisted along with the yarn d d, passes to the flier from a bobbin E or a suitably-arranged can. The rollers D D' are allowed to be revolved freely

by the friction of the yarn produced by the weight of the upper roller D'.

F is a spool arranged near the opposite end of the flier to the rollers D D', and having a positive rotary motion imparted to it by a band f from suitable driving apparatus. The flier has also a positive rotary motion imparted to it by a band g from the driving apparatus.

The sliver or roving e, which may be drawn and prepared in the usual way before being brought to this machine, or by suitable mechanism while on its way to the machine, enters the flier through the central opening c in the head a next the rollers D D', and thence passes through guides h h', attached to one side of the flier, and thence to the opening c in the other flier-head a'. The yarn d d passes from the bobbin C through guides i i, attached to the other side of the flier and thence to the opening c in the flier-head a', where it meets the sliver or roving e e, and from whence both pass together to the bobbin F. The revolution of the flier causes the sliver or roving e e to be spun between itself and the rollers D D', and at the same time causes the said sliver or roving after being spun to be twisted with the yarn d d between their point of meeting and the spool F, which by its revolution on its axis takes up the twist thus produced. It will be observed on examination that the twist given to the sliver or roving e e between the rollers D D' on the flier is the reverse of that produced in twisting it with the yarn d d, the direction and amount of whose previously-produced twist must also correspond with that given to the sliver or roving e e.

It will be obvious to all persons skilled in the spinning and twisting process that by spinning the sliver or roving e e by the operation of making the twist the machinery which would otherwise require to be used to spin it is dispensed with, and the time that would be occupied in spinning it is saved, besides which the said sliver or roving is spun into yarn without a traverse motion on the flier. The flier operated in this way may be made to carry two or more spools of spun yarn, so that the sliver e e may be twisted along with two or more yarns, instead of with one, as above described.

A circular plate or disk occupying the position of the flier-head a' may be substituted as the equivalent of the flier to carry the bobbin C, and the sliver or roving e e may be conducted through the center of the bobbin, while the yarn d d passes through a guide attached to the said disk, by which the same effect will be produced, and by thus dispensing with the flier the speed may be increased.

What I claim as my invention, and desire to secure by Letters Patent, is—

The application of the flier B or its equiva-

lent, substantially as described, in combination with the rollers D D' and spool F, or other equivalent means of holding the sliver and taking up the twist produced by the flier, whereby the same operation is made to spin the sliver into yarn and twist the same with one or more other yarns simultaneously, as herein set forth.

GEORGE W. PITTMAN.
